UNITED STATES PATENT OFFICE.

GEORGE E. NORTHRUP, OF STAMFORD, CONNECTICUT, ASSIGNOR TO RED STAR APPLIANCES, INC., OF STAMFORD, CONNECTICUT, A CORPORATION OF DELAWARE.

MAILING MACHINE.

Application filed December 31, 1925. Serial No. 78,524.

The present invention relates to machines for sealing envelopes, and for printing with ink on the face of the envelope, as, for instance, to cancel a Government stamp 5 that previously has been affixed on the envelope and to place adjacent to the cancelled stamp the name of the post office, the date and hour of cancellation, and the permit number of the user. The machine is also of service for counting envelopes, cards, and other flat objects, and can be used for printing small inscriptions thereon simultaneously with the counting.

Although the machine is capable of a wide variety of uses, it is intended particularly for sealing stamped envelopes, and then cancelling the Government stamp and counting the number of stamps so cancelled.

Envelopes to be used in this may be of the character now furnished by the United States Government, and having the postage stamp formed directly in the paper of the envelope, or equally well, may be plain envelopes to which adhesive Government stamps have been affixed.

When the sealed envelopes come from the machine with the stamps cancelled, and with the name of the post office and the date printed thereon, they can be delivered in bulk to the post office and there can be distributed directly into the outgoing pouches without the delays and labor incident to first placing them face up on the sorting table and then passing them through the stamp cancelling device now commonly used by the Government employees. In other words, by the use of this machine, much of the labor now done at the post office is done before the mail reaches the post office, with a consequent saving in time in placing the mail in transit to its destination.

The receiving platform of the present machine is so arranged that the envelopes may be stacked with their bodies substantially horizontal and their flaps hanging downward over the edge of the platform, and in shingled relation, a driven roller being provided for advancing the lowermost envelope of the stack into engagement with the feed roller of the machine, and means being provided at the front and on each side of the stack of envelopes for keeping the envelopes in proper alignment.

The machine also embodies a cylindrical barrier above the feed roll and serving to

hold back all but the lowermost envelope of the stack. This barrier or baffle is pivotally mounted so that the wear on it can be distributed over its entire surface.

A moistening device of novel construction and fed with water from a constant level fountain serves to moisten the flap of each envelope during its passage over the feed roll. Transfer rolls and a cooperating inclined plate or guide serve to fold the 60 gummed flap upward against the body of its envelope. Ultimately the forwardly moving envelope trips a printing mechanism which, by a rolling movement over the travelling envelope, cancels the postage 65 stamp and prints adjacent thereto other data, such as the name of the post office, the date and hour of cancellation, and the like. Counting mechanism operatively connected with the printing mechanism records the 70 number of printed imprints, and consequently the number of envelopes, cards, or the like, that have been passed through the printing mechanism. The printing mechanism itself is so mounted that it easily can 75 be removed for adjustment or repair or for changes in the dies and type with which it is equipped. The dies and type are secured in place in novel manner to permit replacement without the aid of special tools. 80

Power for the machine is supplied by an electric motor through a driving belt, the tension of which can be readily adjusted. Anti-friction wood bearings are used wherever needed to insure quiet operation and to 85 obviate the need for oil in places from which it might be distributed to the passing envelopes.

Other objects and details of the complete machine will become clear from the following description taken in conjunction with the accompanying drawings.

Fig. 1 is a side elevation of the complete machine,

Fig. 2 is a plan view of the same with the 100 printing and discharge end removed;

Fig. 3 shows the machine in end elevation as viewed from the intake end;

Fig. 4 is a sectional elevation on the line 105 5—5 of Fig. 1.

Frame-work and receiving platform (Figs. 1, 2, 3 and 4).

The frame work of the machine comprises a cast metal base 1 integral with which are 110

four vertical supporting members 2 and 3 and 4 and 5 arranged in pairs, (Figs. 2 and 3). Connecting members 2 and 3 is an integral transverse stiffening web 6 and connecting members 4 and 5 is a similar web 7. Bolted against the outer edges of members 2 and 4 is a cast metal box 8, the lower face of which rests on base 1 and the upper face of which serves as a support for a horizontal platform 9. The latter extends the entire length of the machine but is cut away at appropriate points to permit rollers to come in contact with the passing envelopes. On the outside of box 8 is a vertical sheet metal plate 10 which serves to cover up certain of the gears and other elements.

At the other side of the machine is a casting of irregular shape comprising a channel 11 having two depending legs 12 and 13, one of which is bolted to supporting member 3 and the other of which is bolted to supporting member 5. Mounted above channel 11 is a horizontal platform 14 which covers up certain of the moving elements.

The receiving platform for the envelopes to be sealed is at the left hand end of the machine, as viewed in Fig. 1, and includes a belt driven drum 15. This drum 15 comprises a cylinder 16 on which are two rubber treads 17 and 18. The cylinder is mounted on a metal shaft 19, the ends of which are secured by bolts 20 and 21 to a pair of brackets 22 and 23 (Fig. 3) carried by platform 9. Attached to the cylinder is a pulley 24 on which runs a belt 25.

When the envelopes are stacked for insertion into the machine, the flaps are adjusted to lie in shingled relation at right angles to the bodies, as indicated in Figs. 1 and 3. The lowermost envelope rests on the rubber treads 17 and 18 of the drum 15, and the weight of the stack of envelopes is relied on to give good frictional engagement with the treads. Each envelope, as it reaches the bottom of the stack, will be advanced into the machine.

The feeding roll and baffles (Figs. 1, 2 and 4).

While an envelope is being advanced by the belt driven drum 15, it is gripped between a large feeding roll or drum 26 and a small cylindrical baffle 27. The feeding drum has a soft rubber tread 28, and has a hub on which is mounted a driving pulley 29. The pulley and hub are secured by a transverse threaded pin 30 to a supporting shaft 31. This shaft passes through anti-friction wooden collars 32 and 33 inserted in the tubular extension 34 of the cast metal box 8, and carries a large gear wheel 35 by which it is driven.

The upper roll 27 is secured to a shaft 36 supported in arms 37 and 38 which are integral with a hub 39 mounted to swing on

a shaft 40. This shaft 40 is mounted on channel 11 and serves as a support for other elements as hereinafter pointed out.

The ends of arms 37 and 38 are connected by a shaft 41 to which is attached a vertical link 42 which passes through a bracket 43 (Fig. 4) and is screw threaded to receive an adjusting nut 44 and lock nut 45. Coiled about this link is a compression spring 46 held between bracket 43 and a collar 47. Upward movement of roll 27 swings arms 37 and 38 about shaft 40 and compresses spring 46.

The upper roll 27 does not rotate freely with a passing envelope, but on the contrary, is held against free rotation by a suitable clutch mechanism, not shown. Due to the restraining action of this clutch, the roll 27 acts as a restraining baffle to hold back the stack of envelopes while the lowermost envelope is being pushed forward by the rubber treads 28 on the feed roll 26.

Supplementing the action of the cylindrical restraining baffle 27 are a pair of inclined baffles 48 and 49, one on each side of roll 27. Each of these baffles is made of sheet metal and has its forward end wrapped around shaft 41. The other end of each baffle passes up between arms 37 and 38 and connects with a horizontal finger 50. Through this finger is threaded a vertical bolt 51 having a lock nut 52 (Fig. 1). The lower end of the bolt rests on hub 39. A tension spring 53 tends to hold the screw in contact with the hub. An adjustment of the screw can be made to regulate the elevation of the baffles 48 and 49 in conformity with the thickness of the envelopes which are being passed through the machine.

The moistening device and its fountain (Figs. 1, 2 and 4).

Bolted to the side of base 1 is a casting 54, shaped to serve as a water receptacle. Threaded into one side of this is a supply pipe 55 on which a water fountain of the constant level type is carried. This fountain comprises a cup 56 with a soft rubber collar 57 into which snugly fits the neck of an inverted glass water bottle 58. At the side of the cup is an overflow opening and air vent 59 slightly above the lower lip of the bottle. Inserted within the neck of the bottle is a soft rubber stopper 60 which fits loosely within the neck and carries at each end an integral enlargement 61. When the bottle is lifted out for refilling, this rubber stopper drops sufficiently to close the neck of the bottle and prevent escape of water, and when the bottle is to be prepared for refilling, the rubber stopper can be pulled out through the neck. After refilling, the stopper is inserted. It makes no difference which end is forced into the bottle, for both ends are alike. The stopper can then be pulled up

ward to close the neck, and when the bottle is restored to the cup 56 and forced down to its final position, the stopper will be lifted by contact with a lug 62 at the bottom of this cup. This fountain serves to maintain a constant level of water within casting 54 from which the water is drawn to moisten the flaps of the envelopes in a manner now to be described.

10 The moistening device includes a rotating metal drum 63 mounted to turn on a stationary stub shaft 64 supported by casting 54. Rigidly secured to the side of this drum is a gear 65 which meshes with a pinion 66 mounted to turn on a pin 67 carried by plate 68. Keyed to pinion 66 is a gear 69 which meshes with a small pinion 70 keyed to a clutch element 71. Both 70 and 71 are mounted to turn on the reduced cylindrical end 72 of stub shaft 64. The element 71 has a slot 73 in its working face. Coacting with this slot is a pin 74 carried by the hub of drum 26 and urged forward into clutching relation by a coil spring 75. With the structure arranged as above described, rotation of drum 26 will cause continuous rotation of the moistening drum 63, but at reduced speed because of the intervening gearing.

30 The use of a clutch between the two elements is of convenience in permitting easy removal of the moistening device for cleaning and repair. By unbolting casting 54 from base 1, the fountain and moistening device can be pulled out of the machine. Then by loosening set screw 76 and pulling on its knurled knob 77, stub shaft 64 can be withdrawn. Then the moistening drum can be lifted out of the water and all of the 40 remaining gears can be entirely removed for cleaning and repair. The moistening drum carries a ring of horizontal bristles 78 whereby the gummed flaps of passing envelopes are moistened with water from the fountain.

45 *The drive (Figs. 1, 2 and 4).*

The source of power is an electric motor 187 secured to base 1 by bolts 188 which slide in slots 189 (Fig. 2) to permit adjustment of 50 the main driving belt 190 with which the machine is equipped. This belt delivers driving power through suitable pulleys, gears and shafts to a pinion 203. The latter meshes with the gear 204 (Fig. 2) on stub shaft 205. Gear 204 meshes with a wide pinion 98 fastened to a shaft 94 (Fig. 1), whereby the transfer rolls are driven. Pinion 98 also meshes with gear 207 (Fig. 1) mounted on a stub shaft 208 and meshing with a gear 35 whereby the feeding drum is driven.

The operation.

65 Envelopes are stacked on the platform one above another in substantially horizontal po-

sition with their flaps hanging downward in shingled relation at the side of the table. The spring pressed side baffle 209, in conjunction with the opposed baffle, keeps the lowermost envelope in alignment with the feeding drum. Envelopes are picked off one by one from the bottom of the stack by the rubber treads 17 and 18 of the belt driven roller 15, and are delivered under the plate 43' which acts as a front baffle. Ultimately a travelling envelope is dragged forward by the feeding drum and slides across the lower face of the relatively stationary cylindrical baffle 27 while at the same time the damp bristles 78 of the moistening drum wipe the gummed flaps. During this operation the flap of the envelope is held against lateral movement by a finger 210 (Fig. 3) on baffle 209 and by an opposed bracket 211 suspended from the top platform 9 of the machine. After the flap of an envelope has passed out of contact with the damp bristles, it is folded against the envelope and pressed into contact therewith by a suitable sealing mechanism. An appropriate imprint is then made on the envelope by a printing device of suitable form, which device includes a recording counter, and the envelope is then ready for delivery to the post office.

The means for adjusting the machine to envelopes of different thicknesses has already been described. To adjust for envelopes of different widths, there is provided at the intake end of the machine (Fig. 3) a baffle plate 215 suspended from a shaft 216 by arms 217 and 218 and locked in position on that shaft by a spring plate 219 which grips the shaft 1 and has a convenient thumb piece by which that gripping may be released to permit shifting of the baffle along the shaft. The lower end of this baffle rests on platform 9.

Changes may be made in details of the machine without departing from the spirit of my invention as defined by the appended claims.

I claim:

1. In a machine of the character described, the combination of a feeding drum by which envelopes are forwarded into the machine, a rotary brush coaxial with said drum and across the face of which the flaps of the envelopes are wiped to moisten the gum thereof, and a driving connection between said drum and said brush to slowly and continuously turn said brush.

2. In a machine of the character described, the combination of a feeding drum over which envelopes may pass with their bodies horizontal and their flaps vertical, a rotary moistening device coaxial with said drum and across the end face of which the envelope flaps are wiped to moisten the gum thereof, and means for continuously rotating said brush.

3. In a machine of the character described, the combination of a feeding drum, a brush coaxial therewith, and a driving connection between said drum and said brush, including a clutch and speed reducing gearing, substantially as described.
4. In a machine of the character described, the combination of a base, a well bolted thereto, a rotary brush positioned to turn in said well, a feeding drum, and a driving connection between said drum and said brush, including reduction gears and a clutch at which said driving connection can be broken when said well is unbolted from said base.
5. In a machine of the character described, the combination of a rotary brush for moistening the gummed flaps of the envelopes, a well in which said brush dips, gears through which said drum is driven, and a shaft on which said drum is mounted, said shaft being axially removable to permit withdrawal of said brush and its gears from said well.
6. In a machine of the character described, the combination of a feeding drum, a brush supporting drum coaxial therewith, and a detachable geared connection between said feeding drum and said brush supporting drum.
7. In a machine of the character described, the combination of a base, a well bolted thereto, a rotary brush positioned to turn in said well, a feeding drum, and a driving connection between said feeding drum and said brush including reduction gears carried by a wall of said well.
8. In a machine of the character described, the combination of a base, a well bolted to said base, means connected to and supported by said well for maintaining a constant level of water therein, a rotary brush journaled on a shaft carried by the walls of said well and arranged to have its bristles immersed in the water in said well when rotated, a rotary driving means adjacent to said well, and means forming a releasable driving connection between said driving means and said brush including reduction gears carried by a wall of said well.

In testimony whereof I affix my signature.

GEORGE E. NORTHRUP.
